UNITED STATES PATENT OFFICE.

HENRY E. VAN VLECK, OF GREAT BEND, PENNSYLVANIA.

COMBINED MUSIC-RACK AND LEAF-TURNER.

No. 854,129.

Specification of Letters Patent.

Patented May 21, 1907.

Application filed March 14, 1907. Serial No. 362,259.

To all whom it may concern:

Be it known that I, HENRY E. VAN VLECK, a citizen of the United States, and a resident of Great Bend, in the county of Susquehanna and State of Pennsylvania, have invented certain new and useful Improvements in Combined Music-Racks and Leaf-Turners, of which the following is a specification.

My invention relates to improvements in combined music racks and leaf turners.

It has for its object to provide a rack adapted to support music in the proper position on a piano, organ or like instrument and having means adapted to be operated by the knee of the performer for successively turning over the leaves of the music, and thereby leaving the hands absolutely free for playing.

It has for a further object to provide a device of the character set forth embodying advantages in point of perfect operation and simplicity and inexpensiveness of construction.

In the drawings: Figure 1 is a fragmentary front view of a piano having my combined music rack and leaf turner mounted thereon. Fig. 2 a horizontal sectional view taken on the line 2—2 of Fig. 1, looking in the direction of the arrow, and showing one of the leaf turning arms turned over and the parts in position to be operated to turn over another arm. Fig. 3 a view similar to Fig. 2 on an enlarged scale, but showing one of the leaf turning arms turned over and the parts in the position they assume after having released another arm. Fig. 4 a fragmentary vertical sectional view, taken on the line 4—4 of Fig. 1, looking in the direction of the arrow and showing one of the music supporting arms and the clamp at the lower end. Fig. 5 is a perspective view of one of the leaf turning arms and its clamp, and Fig. 6 is a fragmentary detail view of the middle music supporting arm and the clamp on the upper end.

Like reference characters designate corresponding parts in the figures of the drawings illustrating my invention.

Referring to the drawings, 1 designates a piano, 2 the key-board and 3 the ledge above the key-board on which the base 4 of my combined music rack and leaf turner is supported.

To the base 2 are secured upwardly extending rearwardly inclined music supporting arms 5 against the lower ends of which spring clamps 6 bear and serve to hold the outer pages of the music at the bottom and

a spring clamp 7 is mounted on the middle arm to hold the upper edge of the leaves at their fold.

The base 2 at a central point in its front face is provided with a large groove 8 having grooves 9 and 10 extending laterally therefrom through its ends and upwardly extending grooves 11 and 12 leading therefrom through its top.

A vertical shaft 13 is secured at a central point in the groove 8 between the upper and lower walls thereof and around this shaft the spring leaf turning arms 14 are loosely wound one above the other, their rear ends being secured in the rear wall of the groove 8 and the other ends of said arms in their normal or restrained position, extending upwardly through the groove 12 and being provided with clamps 15 for engaging the lower edges of the music leaves.

The leaf turning arms are restrained to the left of the shaft 13 so that their upper ends are in the groove 12, by a spring detent 16, one end of which is secured to the rear wall of the groove 8 and the other end provided with a nose 17 against which the upturned end of the outer leaf turning arm bears.

A rod 19 is slidably located in the recesses 8, 9 and 10 of the base 2 and held therein by a keeper 20 driven into the rear wall of the recess 10, the end 20^a thereof extending into the recess 10 and being turned inwardly so as to come opposite the detent 16 at a point just at the rear of the upturned end of the leaf turning arm bearing against the nose 17, and the other end of said rod 19 being pivotally connected to the upper end of an arm 21 pivotally supported on the piano and having its lower end pivotally connected to one end of a rod 22 slidably supported in keepers 23, 24 and 25 driven into the piano beneath the key board and having its other end 25^a turned downwardly so as to provide for the engagement of the knee of the performer therewith to slide the rod in one direction.

A coil spring 26 is mounted on the rod 22, one end thereof bearing against the keeper 24 and the other end against a collar 27 secured on said shaft and thereby holding the turned down end 25^a of said rod normally in engagement with the keeper 25 and the turned in end 20^a of the rod 19 normally out of engagement with the spring detent 16.

Assuming the parts to be in the position shown by Figs. 1 and 2, to turn a leaf over the performer moves his knee to the right

against the end 25^a of the rod 22 sliding said rod to the right against the action of the spring 26 and through the medium of its pivoted connection with the rod 19 slides 5 said rod to the left bringing the end 20^a thereof against the spring detent 16 between the upturned end of the leaf turning arm bearing against the nose 17 and the upturned end of the adjacent leaf turning arm, 10 thereby moving said detent to the left and releasing the front leaf turning arm to turn over its leaf while restraining the other leaf turning arms behind it, after which the knee of the operator is moved out of contact with 15 the end 25^a of the rod 22 allowing the spring 26 to again expand and restore the rods 19 and 22 and the arm 21 to their normal positions.

I do not wish to be understood as limiting 20 myself to the precise details and arrangements of parts shown and described, but reserve the right to all modifications within the scope of my invention.

Having now described my invention what 25 I claim as new and desire to secure by Letters Patent, is:—

1. In a device of the character set forth, a base having in its front face a central recess, recesses leading therefrom through its ends 30 and recesses leading therefrom through its top, a fixed shaft in said central recess, spring leaf turning arms, one end of each being wound loosely around said shaft and being secured to said base and the other end ex- 35 tending upwardly through a recess leading through the top of the base, a spring detent for restraining said arms in normal position, a reciprocal rod adapted to be moved by the knee of the operator to engage said detent 40 between the two front leaf turning arms and

move it so as to release the front leaf turning arm and means for returning said rod to normal position, substantially as described.

2. In a device of the character set forth, a base, a shaft fixed on said base, spring leaf turning arms, one end of each being wound loosely around said shaft and being secured to said base and the other end extending upwardly, a spring detent engaging the upturned ends of said arms and restraining them in normal position, a reciprocating rod adapted to be moved by the knee of the operator to engage said detent between the two front leaf turning arms and move it so as to release the front leaf turning arm and means for returning said rod to normal position, substantially as described.

3. In a device of the character set forth, a base, spring music turning arms thereon, a spring detent thereon for restraining said arms in normal position, a reciprocating rod mounted thereon, a second reciprocating rod mounted in position to be engaged by the knee of the operator, a pivotally mounted arm pivotally connecting said reciprocating rods, 65 whereby motion is transmitted to the first mentioned rod from the second mentioned rod to move the first mentioned rod into engagement with said detent between the two front leaf turning arms and move it so as to release the front leaf turning arm and means for returning said rods and arm to normal position, substantially as described.

Signed at Great Bend, in the county of Susquehanna, and State of Pennsylvania, 75 this 28th day of February, A. D. 1907.

HENRY E. VAN VLECK.
